(57) **CLAIM**

The ornamental design for a jig for attaching a flexible printed wiring board, as shown and described.

DESCRIPTION

FIG. 1 is a front view of a jig for attaching a flexible printed wiring board showing our new design;
FIG. 2 is a rear view thereof;
FIG. 3 is a top view thereof;
FIG. 4 is a bottom view thereof;
FIG. 5 is a right side view thereof;
FIG. 6 is a left side view thereof;
FIG. 7 is a perspective view thereof;
FIG. 8 is an enlarged view of a portion taken along line 8-8 of FIG. 1;
FIG. 9 is an enlarged view of a portion taken along line 9-9 of FIG. 2;
FIG. 10 is a cross sectional view taken along line 10-10 of FIG. 8; and,
FIG. 11 is an enlarged perspective view of FIG. 8.
The broken lines shown in the drawings represent portions of the jig for attaching a flexible printed wiring board that form no part of the claimed design. The dashed-dot-dashed lines indicate a boundary between the claimed and unclaimed portions of the design.
